CAR ROOF FOR HOPPER CARS

William D. Thompson, Detroit, Mich., assignor
to Hutchins Car Roofing Company, Detroit,
Mich., a corporation of Delaware

Application October 31, 1932, Serial No. 640,531

5 Claims. (Cl. 108—5)

The invention relates to car roofs more particularly designed for use in connection with hopper cars. Such cars are quite generally used for carrying materials which require no protection and where a roof covering is unnecessary. There are, however, uses, such for instance as carrying bulk cement, where the contents must be effectively protected from the weather. Various constructions of roof have been employed for this purpose and which differ from roofs used upon ordinary freight cars in that they must be provided with hatch openings for the loading of the car with the cement or other material. I have discovered that a roof designed for use on ordinary cars and of the type known as flexible can by a slight modification be adapted for use on hopper cars. The invention therefore consists in the novel construction of this modified roof as hereinafter set forth.

20 In the drawings:

Figure 1 is a plan view of a portion of a car roof of my improved construction;

Figure 2 is a similar view of a portion of the roof frame with the roofing plates removed;

25 Figure 3 is a cross section on line 3—3 of Figure 1;

Figures 4 and 5 are cross sections respectively on lines 4—4 and 5—5 of Figure 1.

Figure 6 is a perspective view partly broken away showing the combined junction cap and hatch cover in position.

The type of roof which is modified to form my improved construction is that known as flexible and which is formed by a series of roofing sheets 35 independently movably supported upon the roof frame and secured and weatherproofed by transverse caps, ridge caps, junction caps, etc. As shown in Figures 2 and 3, A are the side plates of the car, B are the carlines extending between these side plates, C are purlines connecting the carlines and arranged on the under side thereof, and D is a ridge pole or purline which is arranged above a central horizontal section of the carlines. The roof cover is formed by roofing sheets E 40 which extend from the ridge to the eaves between the carlines being supported on the purlines, transverse caps F which embrace the carlines and upstanding flanges on the sheets E, ridge caps G embracing upstanding flanges at the upper ends 45 of the sheets on opposite sides of the ridge, and junction caps H which complete the weatherproof joint between the ridge caps and transverse caps. All of the construction thus far described is old and well known in the art. To apply such a construction of roof to an open top hopper car it is

only necessary to place the carlines across between the side plates of the car body, and to use the standard roofing plates, transverse caps, ridge caps, junction caps, etc., for covering the greater portion of the frame. It is, however, necessary to provide hatch openings for the loading of the cement or other material which I have accomplished as follows:

At one or more points in the roof frame, the ridge pole or purline may be cut away between a pair of adjacent carlines and cross members I are placed between the carlines and spaced upon opposite sides of the ridge to leave a hatch opening of the desired area. Between these cross members I and the eaves the roof is covered by roofing sheets E' which are the same in construction as the roofing sheets E but are shorter, so as to terminate above the members I. Short transverse caps F' are weatherproofed between the opposite sides of the sheets E' and the adjacent sheets E. This leaves an uncovered opening between the cross members I and the carlines to which they are attached which serves as the hatch opening for loading material into the car. To cover and weatherproof this opening, a special cap is employed which performs the double function of a hatch cover and a junction cap for weatherproofing between the several roof covering elements which surround the hatch opening. Thus as shown, the hatch cover cap J is fashioned at its opposite ends to embrace the transverse carline caps F' and also the ridge cap G being provided with a depressed flange J' which extends within the pan formed by the upstanding side and ridge flanges of the roofing sheet E. The cap is provided with depressed flanges J² along its margins on opposite sides of the ridge, which fit within the pan formed by the upstanding side and upper end flanges of the roofing sheets E'. Thus the joints on all sides are thoroughly weatherproofed, while the central portion of the cap extends to cover the space between the carlines and the cross members I. The cap is secured in position by shoulder bolts K which engage apertures in the upper ends of the transverse caps F' and extend downward through the carlines, being secured by a clamping nut K' and a spacer collar K². Above the shoulder K³ on the bolt is an extension which passes through apertures in the cap J and is engaged by a clamping nut K⁴ for securing said cap firmly in place.

The roof is provided with the usual running boards L supported upon saddles M, but to avoid interference with the hatch opening these running boards terminate on opposite sides thereof.

To complete the running board the cap J has mounted thereon the saddles M' which support short running board sections L' extending between the ends of the running boards on opposite sides thereof.

With the construction as described when it is desired to load the car, all that is required is to remove the nuts K⁴ from the bolts K and lift the cap J, together with the running board sections L' off from the bolts, thereby uncovering the hatch opening. When the car is loaded, this cover may be quickly replaced and will complete the weatherproof protection of the roof.

What I claim as my invention is:

1. The combination with a roof frame including carlines, of roofing sheets supported on said frame extending between carlines upon opposite sides of the ridge and provided with upstanding flanges along their side edges and across their upper ends, the upper end of one of said sheets between a pair of carlines terminating at a point spaced from the ridge to leave a hatch opening, transverse caps and ridge caps for weatherproofing between said sheets surrounding said hatch opening, and a junction cap forming a weatherproof joint with said surrounding sheets and caps and extending across to cover said hatch opening.

2. The combination with a roof frame including carlines, of roofing sheets supported on said frame extending between carlines upon opposite sides of the ridge and provided with upstanding flanges along their side edges and across their upper ends, the upper end of one of said sheets between a pair of carlines terminating at a point spaced from the ridge to leave a hatch opening, transverse caps and ridge caps, for weatherproofing between said sheets surrounding said hatch opening, a junction cap forming a weatherproof joint with said surrounding sheets and caps and extending across to cover said hatch opening, and means for removably clamping said junction caps in position.

3. The combination with a roof frame including carlines, of roofing sheets supported on said frame extending between carlines upon opposite sides of the ridge and provided with upstanding flanges

along their side edges and across their upper ends, the upper end of one or said sheets between a pair of carlines terminating at a point spaced from the ridge to leave a hatch opening, transverse caps and ridge caps, for weatherproofing between said sheets surrounding said hatch opening, a junction cap forming a weatherproof joint with said surrounding sheets and caps and extending across to cover said hatch opening, running boards mounted upon said roof terminating upon opposite sides of said hatch opening, short complementary running boards mounted on said cap and means for removably clamping said cap and short running boards in position.

4. In a car roof, the combination with a roof frame including carlines, and a ridge purline having a section between a pair of carlines removed, of cross members between said pair of carlines spaced on opposite sides of the ridge to form a hatch opening therebetween, roofing sheets supported on said frame extending between carlines and provided with upstanding side and upper end flanges, the sheets between the carlines forming a hatch opening terminating at their upper ends adjacent to said cross members, transverse caps and ridge caps for weatherproofing between sheets surrounding said hatch opening, a junction cap forming a weatherproof joint with the sheets and caps surrounding said hatch opening and extending across to cover said opening, and clamping bolts engaging the corners of said cap to removably secure the same in position.

5. In a car roof, the combination with a roof frame including carlines of independently movable roofing sheets supported on said frame on opposite sides of the ridge, one of said sheets being shortened to leave a hatch opening between its upper end and the ridge, transverse caps for weatherproofing between adjacent sheets, ridge caps for weatherproofing between sheets on opposite sides of the ridge, and a junction cap for weatherproofing between ridge caps and transverse caps, said junction cap extending to cover said hatch opening and being removable to uncover said opening.

WILLIAM D. THOMPSON.
